UNITED STATES PATENT OFFICE.

CHESTER T. ALLCUTT, OF WILKINSBURG, PENNSYLVANIA, ASSIGNOR TO WESTINGHOUSE ELECTRIC AND MANUFACTURING COMPANY, A CORPORATION OF PENNSYLVANIA.

PROTECTIVE DEVICE.

Application filed February 8, 1918. Serial No. 216,088.

To all whom it may concern:

Be it known that I, CHESTER T. ALLCUTT, a citizen of the United States, and a resident of Wilkinsburg, in the county of Allegheny and State of Pennsylvania, have invented a new and useful Improvement in Protective Devices, of which the following is a specification.

My invention relates to discharge gaps as used, for example, in lightning arresters, and it has for its object to provide apparatus of the character designated that shall operate selectively in permitting current passage therethrough, preferably having a low impulse ratio or, in other words, permitting the passage of high-frequency currents at equal or lower voltages than currents of normal frequency.

In the accompanying drawing, Figs. 1 to 8, inclusive, are side views, partially diagrammatic, illustrating various forms of my invention, and Figs. 9 and 10 are diagrams illustrating the much greater degree of protection afforded by a discharge gap having a low impulse ratio than by one having a high impulse ratio.

The use of discharge gaps in connection with transmission lines is well known, said gaps being connected between line and ground and between line and line, either directly or in series relation with other protective apparatus such, for example, as electrolytic arresters.

The function of discharge gaps of the character specified is to permit the passage of currents of abnormal voltage such, for example, as switching surges and lightning disturbances; at the same time preventing the passage of currents of normal voltage.

Disturbances of abnormally high frequency are particularly destructive in their action because of their tendency to cause a very high electromotive force between adjacent turns of electrical windings, and, as it is desirable to discharge said abnormal-frequency electromotive forces, even before they have attained line voltage, I propose to construct a device which shall be selective with respect to frequency, discharging at equal or lower voltages at high frequency than at low frequency. To this end, I provide an auxiliary electrode or antenna in a main discharge gap and I connect said antenna to the respective members of the gap through impedance devices of dissimilar

character, the relative impedances of said connections, at normal frequency, being proportional to the distance of the antenna from the respective gap terminals, whereby said antenna is at the potential of that portion of the electrostatic field, produced by the main electrodes, in which it lies and, therefore, does not disturb the electrostatic conditions within the main gap.

Upon the occurrence of a disturbance of other than line frequency, the two connections of said antenna do not change proportionately in impedance, and potential other than that of the adjacent portion of the field of the main electrodes is impressed upon said antenna, disturbing the electrostatic conditions in the gap. The voltage between the antenna and one of the gap members is rendered so great as to break down said portion of the main gap, whereupon the entire voltage of the line is impressed on the remainder of the gap, this effect, together with ionization, resulting in the immediate breakdown of the entire gap.

By suitably proportioning the different parts of the device, it is possible to construct a gap which will withstand 100,000 volts at 60 cycles but which will break down at 60,000 volts, with a single high-frequency impulse in the line.

Referring to Fig. 1 of the drawing for a more detailed understanding of my invention, I show a line wire at 11, said wire being connected to a horn-shaped discharge member 12. An opposing horn member 13 is connected to ground at 14, either directly or through current-limiting devices, as desired. A small antenna 15 is mounted between the bases of the horns 12 and 13, said antenna being connected to the horn 12 through a condensive reactor 16 and to the horn 13 through a condensive reactor 17 and an inductive reactor 18. The design is such that the ratio of the impedance drop in the reactor 16 to the impedance drop in the reactors 17 and 18, at normal line frequency, is proportional to the distance between the members 12 and 15 and the members 15 and 13 respectively, whereby the antenna 15 does not disturb electrostatic conditions within the gap at the frequency mentioned. Furthermore, the condensive reactors 16 and 17 are of such value that the current passing therethrough at normal frequency is negligible.

If it be assumed that a high-frequency charge flows through the line wire 11, the impedance drop in the condensive reactor 16 is greatly decreased, whereas that in the inductive reactor 18 is largely increased, causing the antenna 15 to approach the horn 12 in potential and imposing a large portion of the high-frequency electromotive force upon the gap 13-15, whereupon said small gap breaks down, immediately followed by the break-down of the entire gap.

In the system of Fig. 2, the general arrangement is as in Fig. 1 except that the antenna 15 is connected to the member 12 through a condensive reactor 16 and a resistance member 19, whereas the connection to the horn 13 is established through smaller condensive reactance, as indicated at 20. Adjustment is so made that the antenna 15 is at the potential of the surrounding medium at normal frequency and so that, with increased frequency, the impedance drop between the members 13 and 15 is decreased much more in proportion than is the impedance drop between the members 13 and 12, whereby the gap is again broken down. The system of Fig. 2 is to be preferred to that of Fig. 1 for many purposes as it is more convenient to install a resistance rod 90 having suitable impedance than to install an equivalent inductive reactor.

The system of Fig. 3 is similar to that of Fig. 2 but indicates the possibility of employing condensive reactors 16 and 17 of equal size in the connections to the horns and unbalancing the circuit by an ohmic resistor 19.

In the system of Fig. 4, connection is made from the horn 12 through a condensive reactor 16 to a terminal of an inductive reactor 21, and a connection is made from the horn member 13 through a condensive reactor 17 to an intermediate point in said inductive reactor 21, the antenna 15 being connected to the remaining terminal of the inductive reactor 21. The operation of the system thus indicated is similar to that of Fig. 1 except that, upon the occurrence of a high-frequency impulse, the auto-transformer action of the reactor 21 still further increases the field disturbing action of the antenna to ensure an effective break-down of the gap.

In the case of an extremely long gap, such as is employed in high-voltage transmission systems, it may be desirable to employ two or more antennæ disposed at different points within the gap. Thus, in the system of Fig. 5, two antennæ 15 and 24 are disposed in the gap between the horn members 12 and 13. Connection is made from the horn member 12 to the base of the antenna 15 through a condensive reactor 16 and an ohmic resistor 19. Connection is made between the bases of the respective

antennæ through a condensive reactor 22 and an ohmic resistor 23. Connection is also made between the base of the antenna 24 and the horn member 13 through a condensive reactor 17. Under normal conditions, the impedance drops in the various portions of the charging circuit are such that the antennæ 15 and 24 remain at the respective potentials of the surrounding media. The resistor 19 is preferably larger than the resistor 23, in consequence of which a high-frequency surge produces a greater impedance drop between the horn member 12 and the antenna 15 than between the two antennæ, and the initial breakdown occurs at 80 the gap 15-12. The consequent flow of current through the devices 22 and 23 immediately so increases the impedance drop between the two antennæ as to produce a breakdown therebetween, whereupon the entire 85 gap breaks down.

The high-frequency-impulse-discharge voltage of a gap of this nature is not radically changed by a change in the shape of the main electrodes, whereas the discharge 90 voltage with reference to low-frequency electromotive forces may be profoundly modified by a change in the shape of the electrodes.

Thus, a sphere gap, as is well known has a 95 much higher breakdown voltage with respect to electromotive forces of low or commercial frequency than a gap of the same length having electrodes of restricted area.

By constructing a discharge gap in accordance with my invention, therefore, wherein the main electrodes have large radii of curvature, as by being spherical in contour, whereas the discharging antenna is restricted in area, a great decrease in the impulse 105 ratio is obtained, with resultant more effective protection.

I will show in Fig. 6 a gap of this character, sphere members 25 and 26 being arranged to act as the seat of the main discharge, said discharge being brought about by an antenna arranged, for example, as in Fig. 2, although any of the other arrangements shown or still other equivalent arrangements may be employed for the energization of the antenna. The field distribution between the spheres 25 and 26 is such that a more radical disturbance may be produced therein by the antenna 15, with a given voltage impressed upon said antenna. 110 115 120

In the form of my device shown in Fig. 7, the arrangement is similar to that of Fig. 6 but the antenna itself terminates in a sphere or similar enlarged member 27, whereby still further modification of the discharging 125 characteristic is obtained. A noteworthy feature of the system of Fig. 7 is that the antenna 27, having an extended surface, is not burned or pitted by discharges, whereby the discharging characteristic is but little 130

affected by repeated operation, in distinction to those forms of my device wherein a pointed antenna is employed.

The system of Fig. 8 illustrates a commercial form of the apparatus indicated in Fig. 6. The line wire 11 is connected to a horn member 12 which is supported by a corrugated insulating pillar 28 resting upon a pillar-type insulator 29, said pillar-type insulator comprising a series or column of insulating members 30 separated by conducting supporting members 31, as is well known in the art. The horn member 12 is provided with a discharge member 32, of hemi-spherical contour, at its base, said member facing an antenna 15 supported at an intermediate point in the pillar-type insulator 29. An insulator 33 carries a spherical discharge member 34 opposing the discharge member 32 and further carries a corrugated insulating member 35 supporting a horn member 36 opposite the horn member 12. The line wire 11 is connected to the upper conducting member of the pillar insulating member 29 through a high-resistance member 37 and the horn 36 is similarly connected to the discharge member 34 through a resistor 38, the element 34 being connected to ground, either directly or through an electrolytic arrester 39 or equivalent current-limiting means. The function of the insulating members 28 and 35 is to remove the horn members 12 and 36 to a considerable distance from the metal portions of the insulators 29 and 33, whereby the capacity to said conducting portions is greatly reduced. The metallic members 31 of the pillar-type insulator 29, together with the insulating members 30, produce a series of small condensers, two of which are indicated as inserted between the base of the antenna 15 and the lower end of the resistor 37 and the remaining two of which are connected between the base of the antenna 15 and the horn 36 through the metal supporting member 40, the pin 41 and the condenser established between the upper end of the pin 41 and the support for the member 34. The resistor 37 corresponds to the resistor 19 in Figs. 2 and 3 and operates to produce an unbalance in voltage between the antenna 15 and the main electrodes 32 and 34, as in the previously described systems. The resistor 38 is normally used as the charging resistor for the arrester 39, the horns 36 and 12 being arranged for conjoint movement for this purpose, if desired. High-frequency surges pass directly between the members 32 and 34 by the action of the antenna 15 and thence to ground through the arrester 39. Low-frequency surges and high voltages of normal frequency discharge from the member 12 directly to the horn 36 and thence, through the resistor 38 and the element 39, to ground. If the discharge

between the member 32 or the horn 12 and the horn 36 becomes excessive, sufficient voltage drop is produced in the resistor 38 to break down the gap to the member 34, whereupon the discharge follows the latter path.

Throughout this application, I have laid emphasis upon the low impulse ratio attainable with the discharge gap shown. The beneficial effects of such a construction are illustrated in connection with Figs. 9 and 10.

Referring to Fig. 9, assume that line voltage is indicated by a wave 42 and that a discharge gap requiring twice line voltage for its breakdown is employed. If a gap having an impulse ratio of, for example, unity, which is substantially the lowest value heretofore attained, be employed, a voltage impulse, shown at 43, occurring at the crest of the supply wave, and in such a direction as to add thereto, will attain a value equal to line voltage before discharge occurs. Although an impulse of this magnitude may cause an excess voltage between adjacent turns of electrical apparatus, it will not necessarily damage properly insulated apparatus. For an impulse adding to a low-frequency supply wave, then, an ordinary gap having an impulse ratio of unity may afford sufficient protection. If, however, the impulse occurs at the crest of the low-frequency wave but in such a direction as to subtract therefrom, as indicated at 44, it is seen that the impulse may attain a magnitude equal to three times line voltage before discharge occurs, i. e., before a voltage equal to twice line voltage is impressed across the gap. Such an impulse is liable to cause very destructive voltages between turns of inductive apparatus.

Fig. 10 shows the action of an arrester made in accordance with my invention. Assume, as before, that the gap be so adjusted that the low-frequency discharge voltage is equal to double line voltage; 45 indicates the relative magnitude of an impulse, adding to the low-frequency wave, that is required to cause discharge. It is seen that, because of the selective action of the gap, discharge will occur before the total voltage across the gap reaches double line voltage. 46 indicates the relative magnitude of impulse required to cause a discharge when said impulse occurs at the peak of the low-frequency wave but in such a direction as to subtract therefrom. Even in this case, an impulse of very little over-line voltage is sufficient to cause discharge. Effective protection is thereby afforded even under the most unfavorable conditions.

It is well known that the breakdown potential of a discharge gap depends, to a considerable degree, on the distribution of the electrostatic field between the discharge gap members and that the breakdown potential

of a gap of given length and of non-uniform potential gradient is lower than that of a similar gap of uniform potential gradient.

From the foregoing description of my invention, it will be obvious that, at frequencies higher than normal, the auxiliary electrode of my invention will tend to render the potential gradient of this field less uniform, and that its distorting effect will be proportional to the difference between the existing frequency and normal frequency.

While I have described my apparatus in a plurality of preferred forms, it will be obvious to those skilled in the art that it is susceptible of various minor changes and modifications without departing from the spirit thereof; and, I desire, therefore, that only such limitations shall be placed thereupon as are imposed by the prior art or as are indicated in the appended claims. I claim as my invention:

1. In protective electrical-discharge-gap apparatus, the combination with two discharge members mounted in spaced relation to each other and connected to a supply circuit, of an auxiliary electrode mounted adjacent said discharge members, and connections embodying impedance members of dissimilar character between said auxiliary electrode and said discharge members, respectively.

2. In protective electrical-discharge-gap apparatus, the combination with two discharge members mounted in spaced relation to each other and connected to a supply circuit, of an auxiliary electrode mounted adjacent said discharge members, and connections embodying impedance members of dissimilar character between said auxiliary electrode and said discharge members, respectively, said connections having impedances, at the normal frequency of said circuit, substantially proportional to the distance between said auxiliary electrode and said discharge members, respectively.

3. In protective electrical-discharge-gap apparatus, the combination with two discharge members mounted in spaced relation to each other and connected to a circuit of an auxiliary electrode mounted adjacent said discharge members, and means whereby, at the normal frequency of said circuit, said auxiliary electrode is maintained at substantially the potential of the immediately adjacent electrostatic field set up by said discharge members, and whereby, at other frequencies in said supply circuit, said auxiliary electrode is so charged as to disturb said electrostatic field.

4. In electrical spark-discharge-gap apparatus, the combination with two discharge members mounted in spaced relation to each other and connected to a circuit, of an auxiliary electrode mounted adjacent said dis-

charge members, connections between said auxiliary electrode and said discharge members, respectively, and impedance devices in said connections, the net capacitance of one connection preponderating over that of the other connection.

5. In protective electrical-discharge-gap apparatus, the combination with two discharge members mounted in spaced relation to each other and connected to a circuit, of an auxiliary electrode mounted adjacent said discharge members, and connections embodying capacitative reactors between said auxiliary electrode and said discharge members, respectively.

6. In electrical spark-discharge-gap apparatus, the combination with two discharge members mounted in spaced relation to each other and connected to a circuit, of an auxiliary electrode mounted adjacent said discharge members, and connections embodying capacitative reactors between said auxiliary electrode and said discharge members, respectively, the net capacitance of one of said connections exceeding that of the other of said connections.

7. In protective electrical-discharge-gap apparatus, the combination with two discharge members mounted in spaced relation to each other and connected to a circuit, of an auxiliary electrode mounted adjacent said discharge members, and connections embodying impedance devices of such character between said auxiliary electrode and said discharge members that, upon a change in the frequency applied thereto, the net impedances of said connections change at different rates.

8. In electrical spark-discharge-gap apparatus, the combination with two discharge members mounted in spaced relation to each other and connected to a circuit, of an auxiliary electrode mounted adjacent said discharge members, and connections embodying impedance devices of such character between said auxiliary electrode and said discharge members that, upon a change in the frequency applied thereto, the net impedances of said connections change at different rates, the impedances of the respective connections, at the normal frequency of said circuit, being substantially proportional to the breakdown voltages of the gaps provided between said auxiliary electrode and the corresponding discharge members.

9. In protective electrical-discharge-gap apparatus, the combination with two discharge members mounted in spaced relation to each other and connected to a circuit, of an auxiliary electrode mounted adjacent said discharge members, a connection embodying a resistor and a condensive reactor between said auxiliary electrode and one of said discharge members, and a connection embodying a condensive reactor between

- said auxiliary electrode and the remaining discharge member.
10. In electrical spark-discharge-gap apparatus, the combination with two discharge members mounted in spaced relation to each other and connected to a circuit, of an auxiliary electrode mounted adjacent said discharge members, a connection embodying a resistor and a condensive reactor between said auxiliary electrode and one of said discharge members, and a connection embodying a condensive reactor between said auxiliary electrode and the remaining discharge member, the impedances of the respective connections, at the normal frequency of said circuit, being substantially proportional to the breakdown voltages of the gaps provided between said auxiliary electrode and the corresponding discharge members.
11. In an electrical-discharge device, means providing a discharge gap, an auxiliary electrode disposed to assist in the breakdown of said gap, and means embodying a condensive reactor connected between said auxiliary electrode and another portion of said discharge device, said condensive reactor being formed, in part, by an insulator serving to insulate said device.
12. In an electrical-discharge device, means providing a discharge gap, an auxiliary electrode disposed to assist in the breakdown of said gap, and means embodying a condensive reactor connected between said auxiliary electrode and another portion of said discharge device, said condensive reactor being formed, in part by a pillar-type insulator.
13. In an electrical-discharge device, the combination with a conducting member, of two insulators mounted adjacent thereto, two discharge members mounted upon said insulators, respectively, and jointly forming a discharge gap, an auxiliary electrode mounted adjacent said gap and connected to one of said discharge members through the condensive reactance of one of said insulators, together with its immediately associated conducting members.
14. In an electrical-discharge device, the combination with a conducting member, of two insulators mounted thereupon, discharge members mounted upon said insulators and jointly forming a discharge gap, an auxiliary electrode mounted in proximity to said gap, and connections from said auxiliary electrode to each of said discharge members through the condensive reactance provided by each of said insulators and its immediately associated conducting members, respectively.
15. In an electrical-discharge device, the combination with a conducting support, of two insulators mounted thereupon and each made up of insulating and conducting members forming condensive reactors, non-conducting extensions on said insulators, discharge horns mounted on the tops of said extensions, a discharge member mounted at the base of one of said extensions and facing the horn on the other insulator, a resistor connected between said discharge member and the horn carried by the same insulator, a resistor connecting the remaining horn to a conducting member of its associated insulator, and an auxiliary discharge electrode mounted adjacent to the main discharge gap and connected to an intermediate conducting member in one of said insulators.
16. A lightning arrester comprising two discharge gaps disposed in series relation, shunt paths embodying dissimilar impedance devices connected across said gaps, respectively, said impedance devices being such that, at the normal frequency at which said arrester is to be operated, the impedance drops therein are substantially proportional to the break-down voltages of the associated gaps, respectively, and at appreciably different frequency, depart from said proportionality.
17. In electrical spark-discharge-gap apparatus, the combination with two discharge members mounted in spaced relation to each other and connected to a supply circuit, of means dependent on the frequency of the supply circuit for modifying the electrostatic field between said discharge members.
18. In protective electrical-discharge-gap apparatus, the combination with two discharge members mounted in spaced relation to each other and connected to a supply circuit, of means dependent on the frequency of the supply circuit for regulating the distribution of the electrostatic field between the two discharge members.
19. In electrical spark-discharge-gap apparatus, the combination with two discharge members mounted in spaced relation to each other and connected to a supply circuit, of means for modifying the electrostatic field between said discharge members, said means being dependent on the frequency of the supply circuit for varying the degree of modification.
20. In protective electrical-discharge-gap apparatus, the combination with two discharge members mounted in spaced relation to each other and connected to a source of electro-motive force, of means modifying the electrostatic field adjacent said discharge members so as to cause a less nearly uniform potential gradient to exist therein at high frequencies than at lower frequencies.
21. In electrical spark-discharge-gap apparatus, the combination with two discharge members mounted in spaced relation to each other and connected to a source of energy, of means modifying the electrostatic field in the path of discharge between said discharge

- members so as to cause a less nearly uniform potential gradient to exist therein at high frequencies than at lower frequencies.
22. In protective electrical-discharge-gap apparatus, the combination with two discharge members mounted in spaced relation to each other, one of said members being connected to a source of electro-motive force and the other being maintained at a potential differing from that of the source of electro-motive force, of means modifying the electrostatic field adjacent said discharge members so as to cause a less nearly uniform potential gradient to exist therein at relatively high frequencies than at normal frequency.
23. An electrical spark-discharge-gap apparatus comprising two electrodes disposed in spaced relation to each other to form a gap, one of said electrodes being connected to a supply circuit and the other being connected to a circuit to which it is desired that the discharge be impressed upon breakdown of the gap, and means dependent on the frequency of said supply circuit for varying the breakdown potential of said gap.
24. The combination with an electrolytic lightning arrester having one side grounded, of a supply circuit, a discharge gap comprising two discharge electrodes disposed in spaced relation to each other, one of which is connected to the ungrounded side of said electrolytic arrester and the other of which is connected to a source of supply, of means for causing the breakdown potential to vary with the frequency of said supply circuit.
25. In a lightning-discharge-gap apparatus provided with two spaced discharge members, means for impressing an electro-motive force of predetermined character thereacross, the method of inducing a discharge between said discharge members comprising modifying the potential gradient therebetween.
26. The combination with an electrical spark-discharge-gap device comprising two spaced discharge members one of which is connected to a source of electro-motive force and the other of which is connected to a circuit to which it is desired that the source of electro-motive force be connected when the discharge gap breaks down, of an auxiliary electrode mounted adjacent to said discharge members and normally electrically connected to both of said discharge members.
27. The combination with an electrical spark-discharge-gap device comprising two spaced discharge members one of which is connected to a source of electro-motive force and the other of which is connected to a circuit to which it is desired that the source of electro-motive force be connected when the discharge gap breaks down, of an auxiliary electrode mounted adjacent to said discharge members and connected to both of said discharge members through impedance devices.
28. The combination with means providing a spark gap, of means for impressing an electro-motive force of predetermined character thereacross, a conducting member disposed in proximity to said gap and means for maintaining said conducting member at the potential of the surrounding field during the existence of said predetermined electro-motive force condition and for causing said conducting member to diverge from the potential of the surrounding field upon a divergence of said electro-motive force from said predetermined character.
29. In a lightning arrester inserted between two leaders and having a number of spark-gaps in series and capacities inserted between one of the leaders and the spark-gap joints, means for equally dividing between the spark-gaps the normal working voltage of the system to be protected.
30. Discharge gap apparatus having an impulse ratio of less than unity.
31. A spark-gap device having a lower discharge voltage at high frequencies than at relatively lower frequencies.
32. In combination with a source of electromotive force, a protective device provided with a discharge gap and means for causing the breakdown voltage of said gap to vary inversely with the frequency of the source.
33. A protective device provided with a discharge gap comprising two spaced electrodes, means for causing the breakdown voltage therebetween to decrease with an increase in the rate of change of potential of one of the electrodes.
34. In a protective device the combination with an electrical-discharge gap device comprising two spaced discharge members one of which is connected to a source of electromotive force and the other of which is connected to a circuit to which it is desired that said source be connected when the discharge gap breaks down, of an auxiliary electrode mounted adjacent to said discharge members and normally electrically connected to both of said discharge members, and means for changing the impedance between said auxiliary electrode and one of the discharge members under predetermined conditions.
35. The combination with an electrical-spark-discharge gap device comprising two spaced discharge members one of which is connected to a source of electromotive force and the other of which is connected to a circuit to which it is desired that said source be connected when the discharge gap breaks down, of an auxiliary electrode mounted ad-

jacent to said discharge members and normally electrically connected to both of said discharge members, and means for changing the impedance between said auxiliary 5 electrode and one of the discharge members upon a change of frequency of said source.

36. The combination with an electrical-spark-discharge-gap device comprising two spaced discharge members one of which is 10 connected to a source of electromotive force and the other of which is connected to a circuit to which it is desired that the source of supply be connected when the discharge gap breaks down, of an auxiliary electrode 15 mounted adjacent to said discharge members and normally electrically connected to both of said discharge members, and means for changing the impedance between said auxiliary electrode and one of the discharge 20 members in accordance with the rate of change of potential of said one discharge member.

37. In combination, a source of electromotive force, a plurality of spark discharge 25 gap devices connected in series, means for causing the breakdown voltages of said gaps to be proportional to the length of said gaps under normal conditions and to differ therefrom under predetermined abnormal 30 conditions.

38. In combination, a lightning arrester provided with a plurality of discharge gaps connected in series, means for causing each of said gaps to have substantially the same 35 discharge voltage under normal conditions and to have relatively different discharge voltages under predetermined conditions.

39. In combination with a source of electromotive force, a plurality of electrodes 40 forming discharge gaps connected in series, and means for causing the breakdown voltages of said gaps to change differently under predetermined conditions of said source of supply.

40. In combination with a source of electromotive force, a connection to ground comprising a plurality of discharge gap devices connected in series, said gaps being so disposed that the ionization of the surrounding medium produced by the breakdown of 50 one of said gaps affects the breakdown voltages of the remainder thereof.

41. In combination with a source of electromotive force, a connection to ground 55 comprising a plurality of discharge gap devices connected in series, and impedance members of dissimilar character connected across each of said gaps.

42. In combination with a source of electromotive force, a plurality of discharge 60 gaps connected in series, and means for causing the voltages across said gaps to be proportional to the breakdown voltage of

said gaps upon normal conditions and to differ therefrom under predetermined abnormal 65 conditions.

43. In combination, a source of electro-motive force, a plurality of members arranged to form discharge gap devices connected in series, means for causing the voltages impressed across said gaps to be proportional to the breakdown voltage of said gaps under normal conditions of said source of electro-motive force and to differ therefrom under predetermined abnormal 70 conditions thereof. 75

44. In combination, two spaced main discharge members of the sphere gap type, and an auxiliary electrode of the needle point type disposed intermediate said main discharge members. 80

45. In combination, two spaced main discharge members of the sphere gap type, and an auxiliary electrode of the needle point type disposed intermediate said main 85 discharge members and connected to both of said main discharge members.

46. In combination with a supply circuit, two spaced main electrodes of the sphere gap type, one of which is connected to the supply circuit and the other of which is connected to ground, an auxiliary electrode of the needle point type disposed intermediate said main discharge members, said needle point electrode being maintained at a potential intermediate that of the two main electrodes, and means for varying the potential of said needle point electrode between the values of potential of the main electrodes upon a change of frequency of 95 said supply circuit. 100

47. A protective device provided with a plurality of discharge gaps in series relation, means for applying an electromotive force across said gaps, and additional means 105 whereby the proportion of said electromotive force impressed across one of said gaps varies under predetermined conditions.

48. In combination, a plurality of discharge gap devices arranged in series relation, means for applying an electromotive force across said gaps, and additional means whereby the proportion of said electromotive force impressed across one of said gaps varies with the rate of change of the said 110 115 electromotive force.

49. A lightning arrester having an impulse ratio of less than unity.

50. A protective device provided with a discharge gap having an impulse ratio of 120 less than unity.

In testimony whereof, I have hereunto subscribed my name this 31st day of Jan., 1918.

CHESTER T. ALLCUTT.
